SHOE SOLE CEMENTING APPARATUS

Herman Haseler, Garfield, N. J., assignor to
 Barge Electric Shoe Cement Press, Inc., Brooklyn, N. Y., a corporation of New York

Application March 2, 1934, Serial No. 713,706

11 Claims. (Cl. 12—33)

This invention relates to apparatus used in cementing soles and half soles to shoe bodies, either in their original construction or for replacement and repairs.

5 Stated in general terms, the object of the invention is to provide a universal apparatus that can be used effectively on various types and styles of shoes without change or substitution of parts and which is yielding flexible and self conforming to the shape of the bottom of the shoe to be soled, irrespective of the curves, humps, depression and uneven surfaces it may have.

10 A further feature is in the provision of means to facilitate setting of the cement, thereby to increase the output of the apparatus fully fifty per cent above normal, while its operation is performed in a particularly rapid, sure and simple manner on one or more shoes at a time.

15 Another purpose is to produce a device embodying means to exert an adjustable spring pressure on the sole, gradually applied and released, and capable of being locked when in operation, preventing displacement of the parts and possible injury to the operator.

20 These and other important objects, which will appear as the description continues, are accomplished by the novel and practical construction and combination of parts hereinafter described and illustrated in the accompanying drawings, constituting a material component of this disclosure, and in which:—

25 Figure 1 is a top plan view of a unitary embodiment of the invention, showing its application.

30 Figure 2 is a side elevational view thereof.

Figure 3 is a front elevational view of the same.

35 Figure 4 is a longitudinal sectional view of the lower part of the apparatus drawn to an enlarged scale.

40 Figure 5 is a transverse sectional view taken on line 5—5 of Figure 4.

Figure 6 is a fragmentary side view showing a modified form of pressure clamp engaging means.

45 Figure 7 is a transverse sectional view taken on line 7—7 of Figure 6.

Figure 8 is a partial sectional view, similar to Figure 4, but showing a modified form of sole cushion adapted to women's shoes having high heels.

50 Figure 9 is a rear elevational view showing the apparatus as arranged for dual operation.

Figure 10 is an end elevational view of the apparatus as adapted for a plurality of shoes simultaneously undergoing soling operations.

55 The simple form of the device shown in Figures

1 to 5, consists of a hollow base 15, preferably an aluminum casting and generally an elongated rectangle in profile, the front end being bowed outwardly and the rear end concave, as seen in Figure 1, the base having a chamber 16 in its upper side and recesses 17—17' in its bottom, below which extend integral feet 18—19 at the front and rear to rest upon a level supporting surface.

The upper edge of the chamber wall is generally curved in conformity with the shape of the sole of a shoe and is formed with an outstanding flange 20 and perpendicular front end wall 21, both of which preferably have in the center of their width a continuous longitudinal groove 22. A fluid passage near one end is provided with a removable closure plug 23, for filling the chamber 16.

5 A flexible diaphragm or blanket 24, such as a sheet of rubber, and an overlying cover 25 of thin leather, is secured over the chamber 16 by metallic strips 26 formed with beads 27 to press the blanket and its cover into the groove 22, when the strips are drawn towards the flange 20 and face wall 21 by a plurality of clamp bolts 28, thereby effectually sealing the fluid chamber 16 and its contents against evaporation and leakage, even when under a very considerable pressure.

In the recess 17, in the underside of the base 15, (see Figures 4 and 5) is an electric heating coil 30 having connections 31 leading to a thermostat in the recess 17' by which the temperature is controlled in the usual well known manner, and provided with connections to any convenient source of current; the coil is held by an aluminum plate 33 fastened to the base 15 by screws 34. The plate 33 is insulated from the electric heating coil 30 by a sheet 32 of material such as asbestos while a second sheet 35 of insulating material is arranged between the plate 33 and a cover plate 36 which encloses the heating unit within the recesses 17 and 17' and is fastened to the base 15 by screws 37.

It is to be noted that heat from the coil is transmitted directly to the bottom of the chamber 16, (see Figures 4 and 5) and communicated to the fluid therein, thus causing rapid heating in a substantially direct manner, very little loss occurring.

A pair of opposed lugs 40 extend upwardly from the rear ends of the strips 26 carrying a bolt 41 by which is hingedly engaged the downreaching end of an inflexible arm 42 extending forwardly at the center of the apparatus over the base.

The rear portion of the pivoted arm 42 is lat-

55

erally enlarged to produce an enclosed housing 43 in which, pivoted on a screw bolt 44, is a hand lever 45, its forward, main portion being of considerable length for convenience of manipulation.

The rear of the lever 45 is shaped to produce a web 46, (see Figures 1 and 2,) integrally formed with a toothed sector 47, operatively engaging the teeth of a plunger rack 48, slideable perpendicularly in the housing 43, at the rear end of the arm 42.

The plunger 48 has on its rear side opposite the rack teeth, a plurality of ratchet teeth 50 engageable with the upper end of a detent bar 51 freely pivoted at 52 in the housing 43 and normally hanging pendant to engage the ratchet teeth by gravity, thus holding the plunger when it is raised.

On top of the plunger is a saddle 54 over which is disposed the central portion of a wire yoke 55, its downwardly extending, divergent arms being formed into eyes 56 engaging the upper ends of a pair of strong helically coiled tension springs 57, connected at their lower ends to eye bolts 58 set in the forward portions of the strips 26.

From the foregoing it will be understood that when the pressure on the lever 45 is depressed, forcing the arm 42 downwardly towards the base, the plunger is raised and held in adjustment by the detent 51.

In order to more thoroughly lock the plunger when raised, a bolt 60, secured by a chain 61 to a bail 62, fixed in the head of the lever pivot 44, may be passed through any of the openings 63 in the sector web 46, thus positively preventing accidental displacement of the lever.

In the reduced web portion of the arm 42, adjacent its lower edge, are two series of openings 65, 66, respectively at the rear and front, and engageable selectively in the rear row is a pin 67, passing through a fork 68 adjustable along the arm and having a block 69 at its lower end suited to adjustably receive a screw stud 70 engageable in an opening in the upper, rear portion of a shoe last X.

Similarly, another pin 71 passes through a like fork 72 to engage in any of the openings 66, the fork having a block 73 adjustably receiving a screw stud 74 engaging the hub 75 of a flexible pad 76 adapted to seat on the forward part of a shoe in which the last X is contained.

In the modified form, shown in Figures 6 and 7, the web of the arm 42 is formed with undulations 78 in its lower edge and parallel therewith are opposed ridges 79 adapted to guide and support movable forks 80 suited to engage the web and ridges in a manner to permit ready adjustment, these forks being provided with pins 81 to engage selectively in the notches of the undulations 78; in other respects the arrangement is the same as previously described and obviously for the same purpose of adjustment in conformity to the size of the shoe being operated upon.

In Figure 9 the same general features appear, the main difference being that the base is adapted to support a pair of the single independently operable devices heretofore described, the base having two upper chambers and lower recesses for the heating means, so that they can operate individually or in pairs.

Figure 10 shows the devices of Figure 9 arranged on a triangular frame 100 mounted for rotation upon a stand 101, thus economizing in space to a far greater extent than is possible with six separate devices.

The electrical connections 34 from each unit are brought to a common center and provided with a manually operable commutator 102 so that individual control is obtainable.

In operation, after the shoe has been placed upon the fluid supported diaphragm, with the sole to be cemented to it, the arm is swung downwardly to engage the cross piece with the forward part of the shoe, the last X being previously positioned in the shoe.

The screw studs may be adjusted to different positions by reason of the selective openings in the web of the arm, whereupon the bight of the yoke is placed in the saddle and the hand lever actuated to raise the plunger, tensioning the 15 springs.

When the proper tension has been obtained, the detent automatically engaging one of the teeth of the ratchet retains the lever in its adjusted position; the lever may be further locked by the 20 pin in an obvious manner.

The pressure on the shoe is released by slightly depressing the lever, to permit withdrawal of the locking pin, and the detent moved by hand from engagement with the ratchet teeth, allowing the lever to rise and free the shoe.

As changes of construction could be made within the scope of the invention, it is intended that all matter contained in the foregoing description or shown in the accompanying drawings 30 shall be interpreted as illustrative and not in a limiting sense.

Having thus described the invention, what is claimed as new and desired to secure by Letters Patent, is:—

1. A shoe sole cementing apparatus comprising a base, an arm hingedly connected therewith and having a housing at its free end, a plunger slideable in said housing provided with a saddle, a yoke engaged on said saddle, springs connecting said yoke and base, and a lever pivoted in said housing to actuate said plunger thereby to tension said springs and cause pressure to bear upon a shoe on said base while cementing a sole thereto.

2. A shoe sole cementing apparatus comprising a base having a cushion to receive a shoe, an arm hinged to said base and having a housing, a plunger slideable in said housing, springs connecting said plunger and base, a lever pivoted in said housing, means associated with said lever to raise said plunger thereby to tension said springs, automatic means for retaining said plunger when raised, and means carried by said arm to transmit the effect of the tensioned springs to a shoe 55 on said cushion.

3. A shoe sole cementing apparatus comprising a base having a cushion to receive a shoe, an arm hinged to said base and having a housing, a plunger slideable in said housing, a yoke on said plunger, a pair of tension springs connecting the ends of said yoke and opposite sides of said base, rack teeth on said plunger, a lever pivoted in said housing and having a toothed sector in engagement with the teeth of said plunger, means to positively lock said sector when under the stress of said springs, and adjustable contacts on said arm to press upon a shoe at different points in its length when disposed on said cushion.

4. A shoe sole cementing apparatus comprising a base having a cushion to receive a shoe, an arm hinged to said base and having a housing, a pair of springs attached to said base, a tension plunger in said housing having rack teeth, a lever pivoted 75

in said housing having a toothed sector engaging said plunger, a yoke connecting said springs to said plunger, ratchet teeth on said plunger opposite the rack teeth, a gravity operated pawl to engage said ratchet teeth, means for positively locking said sector when stressed, and a pair of pressure blocks carried by said arm each respectively adjustable to press against a shoe on said cushion at selected points along its length.

5 5. A shoe sole cementing apparatus comprising a hollow base, a flexible fluid-supported diaphragm in said base, an arm hinged to extend longitudinally over said base, a hand lever pivoted in the outer portion of said arm, said lever having a toothed sector, an upright housing on said arm, a plunger guided in said housing and actuated by said sector, ratchet teeth on the opposite side of said plunger, a detent to engage the ratchet teeth, means to lock said lever against movement, a saddle on said plunger, adjustable front and rear shoe contacts carried by said arm, a pair of springs attached in opposed relation to said base, and a connection between said springs seated in said saddle whereby to resiliently press said arm downwardly upon operation of said lever.

10 6. A shoe sole cementing apparatus comprising a chambered base having a fluid supported cushion, an arm hinged at one end of said base to swing over said cushion, a block adjustably carried by said arm and having a cushioned cross piece adjustable with relation to the front part of a shoe, a second block adjustably carried by said arm to adjustably engage a last within the shoe, a housing on the free end of said arm, a plunger operable therein, said plunger having rack teeth on one side and ratchet teeth on the other, a yoke carried by said plunger, springs connecting the ends of said yoke to opposite sides of said base, a lever pivoted in said housing and having a sector provided with teeth to engage the rack teeth of said plunger, said sector having openings in its web portion, a gravity operable detent to engage the ratchet teeth of said plunger as it is raised, and a locking pin to engage the openings in said sector web.

15 7. A shoe sole attaching apparatus comprising a base, spring means for exerting pressure on a shoe and last positioned on the base, means for distributing the pressure over the length of the

shoe and last, means including a member reciprocable relatively to the pressure distributing means to tension the spring pressure means to apply pressure to the shoe through the pressure distributing means, and means for reciprocating said member.

5 8. A shoe sole attaching apparatus comprising a base, spring means for exerting pressure on a shoe and last positioned on the base, means for distributing the pressure over the length of the shoe and last, means including a member reciprocable relatively to the pressure distributing means to tension the spring pressure means to apply pressure to the shoe through the pressure distributing means, and means for reciprocating said member, and means for holding said reciprocable member in different positions to maintain the spring pressure means under different degrees of tension, as desired.

10 9. A shoe sole attaching apparatus comprising a base, spring means for exerting pressure on a shoe positioned on the base, means for distributing the pressure over the length of the shoe, means including a member reciprocable relatively to the pressure distributing means to tension the spring pressure means to apply pressure to the shoe through the pressure distributing means, and means carried by the pressure distributing means for reciprocating said member.

15 10. A shoe sole attaching apparatus comprising a base, spring means for exerting pressure on a shoe positioned on the base, means for distributing the pressure over the length of the shoe, means including a member mounted in the pressure distributing means and reciprocable relatively thereto for tensioning the spring pressure means to apply pressure to the shoe through the pressure distributing means, and means carried by the pressure distributing means for reciprocating said member.

20 11. A shoe sole attaching apparatus comprising a base, spring means for exerting pressure on a shoe positioned on the base, an arm pivoted at one end thereof to the base and overlying the base for distributing pressure over the length of the shoe, a plunger mounted in the arm and reciprocable relatively thereto for tensioning the spring pressure means, and a lever pivoted to the arm for actuating said plunger.

25 HERMAN HASELIER.
